CLAIM

We claim the ornamental design for a portable generator, shown and described.

DESCRIPTION

FIG. 1 is a first perspective view of a portable generator according to the present disclosure, with portions of the generator shown in broken lines.

FIG. 2 is a second perspective view of the portable generator of FIG. 1.

FIG. 3 is a front view of the portable generator of FIG. 1.

FIG. 4 is a back view of the portable generator of FIG. 1.

FIG. 5 is a first side view of the portable generator of FIG. 1.

FIG. 6 is a second side view of the portable generator of FIG. 1.

The broken line(s) which define the bounds of the claimed design form no part thereof.
